UNITED STATES PATENT OFFICE.

WILLIAM ALFORD HARRIS, OF GALLATIN, TENNESSEE.

HYDROCARBON BURNER.

Application filed November 21, 1922. Serial No. 602,364.

To all whom it may concern:

Be it known that I, WILLIAM A. HARRIS, a citizen of the United States, residing at Gallatin, in the county of Sumner and State 5 of Tennessee, have invented a new and useful Hydrocarbon Burner, of which the following is a specification.

This invention relates to hydro-carbon burners applicable for use in an ordinary 10 cook or heating stove without altering the stove.

The object of the invention is to provide a burner of this character constructed so as to burn kerosene or crude oil by converting 15 it into vapor, also providing for the admixture of heated air with such vapor for complete combustion thereof to obtain a flame of maximum calorific value.

Another object is to provide for such 20 complete combustion as will avoid the exhalation of odor from the burner and the formation of carbon therein.

With the foregoing and other objects in view which will appear as the description 25 proceeds, the invention resides in the combination and arrangement of parts and in the details of construction hereinafter described and claimed, it being understood that changes in the precise embodiment of the invention herein disclosed may be made within 30 the scope of what is claimed without departing from the spirit of the invention.

In the accompanying drawings:—

Figure 1 represents a top plan view of a 35 burner constructed in accordance with this invention and designed for use in a heating stove, and

Fig. 2 is a transverse section thereof taken on the line 2—2 of Fig. 1.

In the embodiment illustrated, the burner constituting this invention which is designed 40 to be placed in the fire box of a stove and preferably to rest on the grate thereof comprises a pan or tray 1, which may be of any desired configuration, being here shown circular and which has an upstanding peripheral flange 2.

This pan 1 is provided at diametrically 45 opposite points with openings 3 and 4 around which are arranged upstanding collars 5 with peripheral shoulders 6 on their inner faces at points spaced from the tops thereof to form seats to support the ends 8 of a manifold 9.

The manifold 9 which is designed for 50 supplying air to the burner is con-

structed substantially U-shaped in form with the tubular legs 8 connected by a tubular cross bar 10 from the lower face of which opens and depends therefrom a 60 branch pipe 11 which is arranged directly over the burner end of the supply pipe presently to be described. A deflector 12 is carried by the lower end of the pipe 11 and may be of any desired configuration being here 65 shown in the form of a disk or annular plate and which projects beyond opposite sides of the manifold and is intended to deflect the flame and spread it to cause it to impinge against the opposite sides of the 70 stove and effect a quick heating thereof.

A brass oil generating pipe 13 is arranged around a recess on the upper edge of the flange 2 for the greater portion thereof, and has one end 14 extended downwardly 75 through the bottom of the pan 1 and is designed to be connected with an oil supply pipe (not shown). The other end of the pipe 13 has a hook-like bend 15 with the terminal 16 thereof extended laterally at 80 right angles to the pipe and which is designed to be positioned directly below the air supply pipe 11 of the manifold as is shown clearly in Fig. 2.

This pan 1 being mounted on the grate of 85 a stove, air will pass up through the grate and enter the manifold through the openings 3 and 4, and be discharged through pipe 11 directly over the oil outlet part of burner proper 16, where it will combine 90 with the gas issuing through this burner 16 and form a combustible mixture.

It will be obvious that when the burner is heated, the oil passing through the coiled pipe 13 will be vaporized and leave the pipe 95 end 16 in the form of gas. To effect the initial heating of the burner, alcohol, gasoline or the like may be placed in the pan 1 and ignited and the heat generated by this burning fuel will operate to heat the coiled 100 pipe 13 and generate gas for combination with the air entering through pipe 11 to obtain a flame of a maximum calorific value and which will consume fuel without the formation of carbon.

The flame produced by the ignition of the combined air and gas beneath the separator 12 will be deflected by said spreader out against the side walls of the fire box of 110 the stove and quickly heat it.

From the above description it will be seen

that this burner which is extremely simple in construction and cheap to manufacture may be placed in any fire box of a stove and that the configuration thereof may be varied to adapt it for use in different forms of stoves, the one here shown being especially designed for use in a heating stove.

The deflector or spreader 12 is not needed for use in cook stoves or small heating 10 stoves, and when the burner is employed in connection with stoves of this character, it may be dispensed with. When used with large heating stoves it is desirable to employ the spreader to deflect the flame to 15 quickly heat the side walls of the stove. It is of course understood that the pipe 13 may be varied in length according to the character of oil used in the burner.

I claim:—

20 1. A burner of the class described comprising a tray having apertures therein, a coiled generator pipe mounted on said tray with one end extending through one of the apertures therein and its other end bent upwardly to form a gas outlet, and an inverted U-shaped manifold having the ends thereof inserted in two of the apertures of said tray and with an opening in the cross bar disposed over the discharge end of the generator pipe.

25 2. A burner of the class described comprising a tray having apertures therein, a

coiled generator pipe mounted on said tray with one end extending through one of the apertures therein and its other end bent upwardly to form a gas outlet, an inverted U-shaped manifold having the ends thereof inserted in two of the apertures of said tray and with an opening in the cross bar disposed over the discharge end of the generator pipe, and a spreader located over said discharge end of the generator pipe.

3. In a burner of the class described, a tray having oppositely disposed openings in the bottom thereof with upstanding collars arranged therearound, a generator pipe mounted on the edge of said tray with one end extending through its bottom, and the other end extending upwardly to form a gas discharge, an inverted U-shaped manifold having the legs thereof seated in said collars with the branch pipe extending downwardly from its cross bar and opening above the discharge end of the generator pipe, and a deflector arranged on said branch pipe above said discharge end of the generator pipe.

In testimony that I claim the foregoing as my own, I have hereto affixed my signature in the presence of two witnesses.

WILLIAM ALFORD HARRIS.
